UNITED STATES PATENT OFFICE.

JAMES MAGNUSEN, OF CHICAGO, ILLINOIS.

DESIGN FOR A LENS FOR SIDEWALKS.

SPECIFICATION forming part of Design No. 26,735, dated March 9, 1897.

Application filed January 28, 1897. Serial No. 621,107. Term of patent 7 years.

To all whom it may concern:

Be it known that I, JAMES MAGNUSEN, a citizen of the United States, residing at Chicago, in the county of Cook and State of Illinois, 5 have invented and produced a new and original Design for Sidewalk Lights or Lenses, of which the following is a specification, reference being had to the accompanying drawings.

Figure 1 is a perspective view showing my 10 design. Fig. 2 is a plan view of the same. These two views are deemed necessary to fully illustrate my design.

The leading feature of my design consists 15 in a circularly-shaped top, a square-shaped base, and a miter-shaped pendant or drop-lens.

A is the top of the sidewalk light or lens, which is circular in its general contour.

B is the base, which is square in its general 20 contour.

Extended from the under side of the base B is a drop-lens or pendant C, which is miter-shaped in its general contour.

What I claim is—

The design for a sidewalk lens or light, substantially as herein shown and set forth. 25

In testimony whereof I affix my signature in presence of two witnesses.

JAMES MAGNUSEN.
